UNITED STATES PATENT OFFICE.

DANIEL BEST, OF SAN LEANDRO, CALIFORNIA.

DESIGN FOR AN ENGINE-FRAME.

SPECIFICATION forming part of Design No. 21,887, dated October 11, 1892.

Application filed August 29, 1892. Serial No. 444,457. Term of patent 14 years.

To all whom it may concern:

Be it known that I, DANIEL BEST, a citizen of the United States, residing at San Leandro, Alameda county, State of California, have invented and produced a new and original Design for Engine-Frames, of which the following is a specification, reference being had to the accompanying drawings, showing a part thereof.

10 Figure 1 is a side elevation. Fig. 2 is a plan view of my engine-frame.

The leading feature of my design is the peculiar outline of the frame in which the two opposing cylinders are fixed, the frame having 15 a peculiar irregular trough shape from the ends to the center and having the two ends out of line with each other in a vertical plane.

10 A A represent those portions of the frame to which the cylinders of the engine are attached at opposite ends. From these ends A sides B, as shown in plan, extend from one end to the other in an irregular curve, the outlines being but little curved upon the diagonally-opposite sides from the ends to the points

where the boxes C of the crank-shaft are secured. From this point each of the sides forms a reverse curve, as shown at B', extending from this curve to the opposite cylinder-support A, this arrangement with these curves being such that the cylinder-supports 25 are out of line with each other in a vertical plane, but lie in the same horizontal plane.

Between these sides is a trough-shaped bottom C', which deepens from the ends to the center, where it reaches its deepest point. From 30 each end reversely-curved ribs D extend downwardly and have feet adapted to rest upon the floor. Between these ribs is a connecting-rib, the ends of which form upwardly-curving arches E, which merge into a downwardly-curving portion F at the center.

What I claim is—

The design for an engine-frame, substantially as shown and described.

DANIEL BEST.
